UNITED STATES PATENT OFFICE.

HEBER C. KLINK, OF TOLEDO, OHIO.

INSTRUCTION DEVICE FOR MUSICAL INSTRUMENTS.

Application filed October 23, 1924. Serial No. 745,391.

This invention relates to instruction devices.

This invention has utility when incorporated in stringed musical instruments of the violin type in which the neck of the instrument is not divided into sections by fretwork or has the notes indicated on the neck by other marking means.

Referring to the drawings:

10 Fig. 1 is a plan view of a violin having the invention herein disclosed incorporated therewith;

15 Fig. 2 is a partial section on the line II-II, Fig. 1, looking in the direction of the arrow;

Fig. 3 is a side view of a violin, parts being broken away, showing the device of the invention herein attached thereto;

20 Fig. 4 is a perspective view of the skeleton frame used in the device herein disclosed;

Fig. 5 is a view showing a modification of the device herein; and

25 Fig. 6 is a view on the line VI-VI, Fig. 5, looking in the direction of the arrow.

Beginners on the violin, cello, bass viol, or viola, must learn to place their fingers upon the proper strings and at the proper places on the strings in order to produce 30 the desired tones or notes. The neck or finger board of this type of instrument is not marked in any manner to aid the pupil in his proper fingering. He must learn to do this guided in two ways that is, his fingers must become accustomed to involuntarily reach the proper distance and his ear must tell him that the note produced is correct. To do this, practice to the fingers and the ear are both necessary. A beginner 35 practicing in private or away from a tutor can easily guide himself into improper finger spacing, likewise accustom his ear to wrong tones which, if corrected early, would save much time in learning. The correction 40 of this difficulty is accomplished by the invention herein.

Stringed musical instrument 1 has neck 2 mounting keys 3 for tuning strings 4 attached thereto and extending therefrom 50 longitudinally of the neck 2 and instrument 1 to be attached to the instrument remote from the keys 3. Strip or member 5 is attached to the neck 2 and serves as a part thereof as well as a finger board against 55 which the player may press the string to produce different tones and notes in accord-

ance with the place upon the string against which the finger is placed.

Skeleton frame 6 has main strips 7 which may be attached to the neck of the instrument, one strip on each side of the neck held closely against the neck by means of bolts 8 having knurled nuts 9. One bolt 8 may extend through openings 10 in the frame 6 and under the strings at the top 60 of the finger board 5 while the other bolt 8 may extend through openings 11 in the frame 6 and under the opposite end of the finger board or member 5. The bolts 65 contact with the strips 7 to create a clamping action holding the frame rigidly with the instrument.

Supplemental bridge strips 12 extend upwardly from the main strips 7 and then transversely across the strings 4 at intervals. The transverse strips 12 serve to mount keys 13 which are manually operable. These keys have fingers coacting with heads or buttons 14 mounted on pins or plungers 15, which pins extend through the strips 12 to have pads 16 mounted thereon. The 75 keys are so mounted that upon depression the pads 16 will coact with the strings 4 to grip the strings 4 against the finger board 5. When not manually depressed the 80 keys are held away from the strings 4 by helical springs 17 around the pins 15 between the heads 14 and strips 12.

The keys are so arranged along the finger board that upon depression the notes of the 85 diatonic scale may be produced, that is the top strip 12, or the one nearest the keys 3, serves to mount one key for producing note F on the E string. Spaced from this strip 90 12 away from the keys 3 is a second strip 95 mounting keys to produce notes A, E, B, on the G, D, and A strings respectively. The next set of stops produce F, C, G, on the D, A, and E, strings, the next strip mounts a key for producing B on the G string. The 100 strips thus far extend but partially across the strings while the next two strips, that is the two most remote from the keys 3, extend entirely across the strings and serve to connect the main frame strips 7 and hold the entire device in a unit. These two strips 105 may also serve to mount stops to produce notes C, G, D, A, on the G, D, A, and E, and notes D, A, E, B, on the same strings. It may be seen that a note to be played may 110 have the corresponding stop depressed to measure the proper string length for produc-

tion of that note. The skeleton frame work allows the fingers to operate upon the strings between the keys for producing the tones of the chromatic scale. The keys each have 5 marked upon its head 14 with the particular letter or symbol 19 produced by that key thus further aiding the pupil in teaching him the different note names.

The keys being held in position as to the 10 strings insure a perfect note to train the ear as well as give the proper finger spacing to train the fingers. The device may be readily mounted upon the instrument with no alteration or marring of the instrument 15 and may be just as readily detached for independent playing.

The device may be somewhat modified as shown in Fig. 6, in which the pads 16 may be carried by leaf springs 18 carried from 20 the main frame strips 7. The device may be stamped from sheet metal and thus add no detrimental weight to the instrument.

Lugs 20 are placed on the side frame members 7 to insure the proper spacing of 25 the pads 16 above the strings 4 and keep the device from slipping. These lugs 20 co-

act with the member 5 and aid in the proper spacing of the keys as to the strings.

What is claimed and it is desired to secure by Letters Patent is:—

1. A skeleton note location instruction device for attaching to the tapering neck of a stringed musical instrument comprising a pair of integral main strips positioned in converging planes, supplemental strips 30 upstanding from the main strips and extending transversely therebetween, to provide clearway regions and keys carried by the supplemental strips unobstructing the clearway 35 regions.

2. An instruction device for attaching to the tapering neck of a stringed musical instrument embodying a frame having a main body, strip members from the main body extending over the diatonic scale note measuring points of the strings of the instrument leaving exposed the chromatic scale points not included in the diatonic scale and keys carried by said strips having contacting 40 pads.

In witness whereof I affix my signature.
HEBER C. KLJINK.
